UNITED STATES PATENT OFFICE

142,480

DESIGN FOR A SCOOP OR SIMILAR ARTICLE

Norris E. Hopkins, Chicago, Ill.

Application March 29, 1945, Serial No. 118,781

Term of patent 7 years

(Cl. D44—29)

To all whom it may concern:

Be it known that I, Norris E. Hopkins, a citizen of the United States, residing at Chicago, in the county of Cook and State of Illinois, have invented a new, original, and ornamental Design for a Scoop or Similar Article, of which the following is a specification, reference being had to the accompanying drawing, forming part thereof.

Figure 1 is a side elevational view of a scoop, or similar article, showing my new design,

I claim:

The ornamental design for a scoop or similar article, as shown.

NORRIS E. HOPKINS.
